UNITED STATES PATENT OFFICE.

WILLIAM A. MARTIN, OF JACKSON, MICHIGAN, ASSIGNOR OF ONE-HALF TO EDWIN H. EHRICH,
OF JACKSON, MICHIGAN.

FENCE-TIE.

No. 918,569.

Specification of Letters Patent.

Patented April 20, 1909.

Application filed June 30, 1908. Serial No. 441,094.

To all whom it may concern:

Be it known that I, WILLIAM A. MARTIN, a citizen of the United States, residing at Jackson, in the county of Jackson and State 5 of Michigan, have invented a new and useful Fence-Tie, of which the following is a specification.

This invention relates to fence ties, a class of devices the office of which is to bind together and hold firmly the horizontal and vertical elements of a wire fence at the points where they cross each other.

The objects of this invention are; the provision in a merchantable form, of a device of 15 the above-mentioned class, which shall be inexpensive to manufacture and facile in application; a device which shall hold the intersecting elements of a wire fence firmly, yet without mutilating them or impairing 20 their tensile strength; the provision of a tie which, by its shape and convolutions, shall grasp the vertical or stay wire in a peculiar and novel manner, bend the intersecting elements into a form adapted to promote the 25 strength of the union, and reinforce the horizontal or line wire, the stay wire, and the tie itself.

With these and other objects in view, as will hereinafter more fully appear, the invention 30 consists in the novel construction and arrangement of parts hereinafter described, delineated in the accompanying drawings, and particularly pointed out in the appended claim, it being understood that 35 various changes in the form, proportions, size and minor details of the structure may be made without departing from the spirit or sacrificing any of the advantages of the invention.

Similar numerals of reference are employed 40 to indicate corresponding parts throughout the several figures of the drawings.

In the accompanying drawings, Figure 1 is a front elevation. Fig. 2 a rear elevation. 45 Fig. 3 a bottom plan. Fig. 4 an end elevation.

The fence tie herein described, is of the 50 staple type and is driven about the intersecting wires and forced into a shape effective to bind them together. As thus formed, it consists of a spiral having its convolutions in close contact, but at no point reentrant laterally upon each other.

The application of the tie to the stay and line wires causes them to be bent; the line 55 wire assuming a forwardly projecting bend at 1, the stay wire assuming a rearwardly projecting bend at 2, the two bends setting into each other at the intersection of the wires. The bends are sufficiently pronounced to form a hold for the tie wire, as hereinafter described, but not sharp enough to weaken the wires. Likewise, in determining the curve to be assumed by the spiral tie, I have regard for the question of economy 60 of material yet making it a consideration secondary in importance to the strength of the tie.

In the accompanying drawings I have shown a horizontal element of a wire fence, or 70 line wire 3, and a vertical element or stay wire 4, bent as heretofore described, and clasping them, the spiral tie of my invention. I shall describe this tie by beginning at its inner end 5 and following its convolutions to 75 its outer end 6.

The inner end 5 is forwardly bent about the stay wire 4 and the continuation of this inner end passes to the rear of the stay wire 4 in close proximity to the line wire 3. It is 80 then bent forward and passes downward across the line wire 3; thence rearward, passing behind and across the stay wire 4; thence forward and upward crossing the front of the line wire 3. Continuing, it passes upward 85 and rearward, engaging the back of the stay wire 4. In the quadrant last above described the first convolution of the stay wire is completed and the second convolution begun. This second convolution from the point 90 where it begins to its terminal 6, is in close contact with the convolution previously made; at no point, however, crossing it laterally or becoming reentrant laterally upon it.

From the back of the stay wire 4, as above 95 described the second convolution passes downward and forward, crossing the front of the line wire 3; thence downward and rearward across the back of the stay wire 4. The outer end 6 is then bent forward about 100 the stay wire 4, in the same manner as the inner end 5. At all points where the first convolution crosses the line and stay wires, it bears laterally in the first instance and vertically in the second against the projecting 105 bends in those members, and both convolu-

tions of the tie wire are in vertical alinement where they cross the tie wire and in horizontal alinement where they cross the line wire.

I invite close scrutiny upon the disposition 5 made of the outer end 6 and the portion of the second convolution included in the quadrant preceding the outer end 6 and I regard the particular form shown, to be of importance, as I shall endeavor to show hereinafter.

10 Of the various kinetic forces which mar the appearance and impair the utility of a wire fence, I know of none more potent than the efforts of human beings to scale the structure. These efforts result in the most perfect 15 downward thrust that I am aware of, and probably represent the maximum strain imposed upon a fence in a downward direction. I have designed this tie with a special regard for strains of this character. It will 20 be seen that the portion 7 is brought into close proximity to the line wire 3; that the portion 7 is reinforced against upward yielding by the second convolution above it; that the portion 7 rests upon the rearward bend 25 2 in the tie wire; and that the inner convolution is braced below the line wire 3 by the clench of the end 6 about stay wire 4, and by the disposition of the portion of the final convolution in the quadrant preceding the end 6.

30 An upward thrust is frequently imparted to the wires of a fence by stock engaging the line wire with their horns and by the efforts of swine to force a passage between the laterals. This upward thrust is resisted by the 35 contact of the lower part of the inner convolution with the rearward bend of the stay wire 4, the disposition of the end 6 and the portion of the tie included in the quadrant preceding, furnishing an important assistance. To the same end, the two convolutions 40 crossing the stay wire 4 above the line wire 3, together with the disposition of the end 5 are of importance.

Opposed to a force tending to shove the 45 stay wire 4 to the left, are, the effect of the forward bends at 5 and 6 about the stay wire 4; the bearing effect at 8, of the single convolution against the forward bend in the line wire 3 and the effect of the double, contacting, convolutions upon the line wire 3.

Opposed to a force tending to drive the stay wire to the right, are, the bearing of the inner convolution against the forwardly projecting bend of the line wire 3; and the reinforcement afforded by the outer convolution; and the friction between the single convolution and the line wire at 8. Against forces 55 in any direction, the bearing of the for-

wardly and rearwardly projecting bends in the line and stay wires, against each other, 60 is of moment.

It should be noticed that the ends 5 and 6 project in the same direction. By this construction it is possible to construct a fence having no projecting parts upon the side of 65 the inclosure next to the stock, thus reducing to a minimum, the chances of the animals becoming injured through contact with the fence.

It will be seen that when the line wire 3, 70 and the stay wire 4 are bent and brought together by the tie as hereinafter described, the ends 5 and 6 being clenched about the stay wire 4, a union is effected which will withstand forces from any direction and of 75 any intensity which it is the practice of fence designers to consider so too, it is regarded of moment that the spiral form of the tie results in a compactness and strength not disclosed by an examination of the prior art. 80

Having thus described my invention, my claims are as follows:—

In a wire fence tie, a line wire; a stay wire; the line wire having a forwardly projecting bend and the stay wire a rearwardly projecting bend, at their point of intersection; a spiral tie wire having its inner end forwardly bent about the stay wire, the continuation of the inner end passing to the rear of the stay wire and in close proximity to the line wire; thence forward and downward crossing the line wire; thence across and to the rear of the stay wire; thence forward and upward crossing line wire; thence rearward across the stay wire and in close contact with the previous convolution of the tie wire; thence forward and downward crossing the line wire and in close contact with the previous convolution of the tie wire; thence across and to the rear of the stay wire and in close contact with the previous convolution of the tie wire, terminating in a forward bend about the stay wire; the inner convolution bearing laterally against the forwardly projecting bend in the line wire and the rearwardly projecting bend in the stay wire; the contacting convolutions alined where they cross the line and the stay wires, in a plane parallel to the plane of the line and the stay wires. 95 100 105

In testimony that I claim the foregoing as 110 my own, I have hereto affixed my signature in the presence of two witnesses.

WILLIAM A. MARTIN.
